WATER CRAFT

John R. Seeley, Rte. 3, Box 20, Aurora, Colo. 80010

Filed Mar. 14, 1966, Ser. No. 1,435

Term of patent 14 years

(Cl. D71—1)

The undisclosed left side and front portions of the craft are mirror images of the corresponding portions shown in FIGURES 3 and 2 respectively.

I claim:

The ornamental design for a water craft, as shown and described.
